UNITED STATES PATENT OFFICE.

ELI BAILEY, OF BRANTFORD, CANADA.

SHEARS OR SCISSORS.

SPECIFICATION forming part of Letters Patent No. 613,617, dated November 1, 1898.

Application filed April 11, 1898. Serial No. 677,206. (No model.)

To all whom it may concern:

Be it known that I, ELI BAILEY, a citizen of the United States, formerly residing in the city of Macon, in the county of Macon and State of Missouri, but now a resident of the city of Brantford, Brant county, in the Province of Ontario and Dominion of Canada, have invented a certain new and useful Improvement in Shears or Scissors, of which the following is a full, clear, and exact description, reference being had to the accompanying drawings, forming part of this specification.

My invention relates to shears or scissors having an adjustment-yoke applied to their pivotal point to bind the two blades thereof together with a requisite amount of pressure to enable the accurate working of the implement; and my invention consists in features of novelty hereinafter fully described, and pointed out in the claims.

Figure I is a side view of a pair of shears constructed in accordance with my invention. Fig. II is a cross-sectional view taken on the line II II, Fig. I. Fig. III is a longitudinal sectional view, taken on the line III III, Fig. I, through the portions of the blades adjacent to the pivotal point, the pivot-pin and yoke being shown in elevation. Fig. IV is an inner face view of the pivot portion of one of the blades. Fig. V is a detail sectional view taken on the line V V, Fig. III.

1 designates one of the shears or scissors blades, having a handle 1^a, and 2 is the other blade, having a handle 2^a. Each blade has a flat bearing-surface 4 (see Figs. III and IV) at the inner portion, and from these flat surfaces the blades are formed with concaves 3, that extend from said surfaces 4 to the points of the blades, the concavity continuing to the end of each blade in conformity to the portions seen in Fig. III. The concave 3 extends from the outer to the inner edges of each blade, and said outer and inner edges are on planes with the bearing-surfaces 4, as is clearly shown in Fig. III. By this arrangement the working of the shears or scissors is rendered extremely accurate by reason of there being a minimum of contacting surfaces throughout the implement.

The blade 1 has a pivot-pin 5 inserted in it and extending beyond the inner face of said

blade. The blade 2 is provided with a cavity 6, that receives the inner end of the pivot-pin 5, the said pin being adapted to fit into 55 said cavity to a nicety to prevent play of one blade on the other. The pivot-pin 5 is provided with a shoulder 5^a, that limits the extent of the insertion of the pin, and it has at its outer end a rounded boss 5^b. The pin 60 is removably seated in the blade 1 in order to allow of its withdrawal during the operation of grinding or sharpening the blade at any time. The blade 2 has a recess 7 in its outer face directly opposite the central portion of the pivot-pin 5.

8 designates a yoke one end of which is provided with a stud 9, adapted to seat in the recess 7 of the blade 2. The other end of the yoke is provided with a cavity 10, that receives and fits over the rounded boss 5^b of the pivot-pin. (See Figs. II and III.)

The yoke 8 has a screw 11 attached to one of its arms and extending beyond said last-mentioned arm. On the free end of the screw 75 is an adjustment-nut 12, whose inner end is provided with a screw-thread that engages the thread of said screw. The nut 12 is formed with a recess 12^a in its outermost portion, that receives a shouldered head 11^a of the screw 80 11. By this arrangement the screw 11 may be made of only sufficient length to allow the nut 12 to be turned onto the screw 11 a sufficient distance to tighten the clamp 8 upon the pivot-point of the shears without the 85 headed or free end of the screw projecting beyond the outer face of the nut, and when the nut is loosened to allow the removing of the clamp 8 for the separation of the shear-blades said nut cannot entirely escape from 90 the screw 11, owing to the shouldered head coming in contact with the base of the recess 12^a and limiting the turning of said nut. Thus the nut is prevented from becoming detached from the screw, in which event it might become lost or misplaced.

While I have shown and described my invention as applied to shears or scissors, I do not limit myself to its use for this particular implement, as besides its use in connection with shears or scissors of all kinds it may be applied with equal facility and advantage in the construction of pliers, forceps, surgical instruments, or other devices of like character.

I claim as my invention—

1. In a pair of shears or scissors, the combination of a yoke having its ends applied to the pivotal point of the blades thereof, and 5 adjusting means applied to said yoke at a point removed from the pivotal point of the blades; substantially as described.

2. In a pair of scissors or shears, the combination of a yoke having its ends applied to 10 the pivotal point of the blades thereof, a screw seated in said yoke at a point removed from the pivotal point of the blades, and extending from one arm thereof through the other arm, and a nut applied to said screw, 15 through means of which the ends of said yoke may be contracted to bind said blades at their pivotal point; substantially as set forth.

3. In a pair of shears or scissors, the combination with the blades thereof, of a remov-

able pivot-pin in one of said blades, the other 20 of said blades being provided with a cavity adapted to receive said pivot-pin, and a yoke applied to said blades at their pivotal point, substantially as described.

4. In a pair of shears or scissors, the combination with the blades thereof, of a yoke adapted to be applied to the pivotal point of 25 said blades, a screw seated in said yoke, a nut on said screw, said nut being provided with a threaded portion adapted to engage said 30 screw, and a recess, and said screw having a shouldered head adapted to fit in said recess, substantially as described.

ELI BAILEY.

In presence of—

E. S. KNIGHT,
STANLEY STONER.
